RIVET SETTING ARM

Frank A. Marty, Los Angeles, Calif., assignor to
Douglas Aircraft Company, Inc., Santa Monica, Calif.

Application August 2, 1943, Serial No. 497,109

3 Claims. (Cl. 78—52)

7

My invention relates to improvements in riveting machines and specifically to parts of such machines effecting the automatic positioning of rivets and cooperating in the operation of upsetting said rivets.

In some known forms of riveting machines, rivets are automatically fed into the rivet holes by a rivet feeding means but the feeding means are withdrawn from the positioned rivet before the rivet is upset. For a complete disclosure of such a riveting machine reference may be had to Berliner U. S. Patent 2,056,559 issued October 6, 1936.

It is an object of my invention to provide improved rivet setting means presenting an unbroken working face acting to clamp the sheet being riveted around the rivet hole and which act to position and thereafter guide the rivet during the upsetting of the rivet.

A further object of the invention is to provide a rivet setting arm which serves both to position the rivet in the rivet hole and to clamp the metal of the parts being riveted adjacent the rivet hole during the upsetting operation and at the termination of said upsetting operation to positively arrest movement of the rivet set thereby preventing deformation of the metal due to said operation.

Another object of the invention is to provide a rivet setting arm having improved means for holding a rivet in position so that the rivet may be accurately registered with the rivet hole.

Still further objects and features of the invention may hereinafter appear from the following description taken in conjunction with the accompanying drawings.

The invention is described and illustrated in a preferred form as applied to a rivet setting arm designed so that it may be substituted for the corresponding part in a known make of riveting machine, but various modifications of the described embodiment of the invention may be made without departing from the scope of the invention as defined by the appended claims.

In the drawings, in which identical numerals indicate identical parts,

Figure 1 is a view in said elevation showing the head of a riveting machine fitted with the rivet setting arm of my invention.

Figure 2 is a perspective view partly in section on an enlarged scale of the rivet setting arm of my invention.

Figure 3 is a detail perspective view showing the arrangement of the pins which are slidably mounted in the rivet shoe of the rivet setting

arm to support the rivet until pushed out of said setting arm by a rivet set.

Figures 4 and 5 are sectional views taken on the line 4—4 of Figure 2 showing the relative positions of a rivet and the positioning pins in the riveting arm shoe at different stages of the operative movement of the rivet set.

Figure 6 is a sectional view taken on the line 4—4 of Figure 2 showing the position of the parts during the final stage of driving the rivet head.

Figure 1 shows the head of a riveting machine in which the device of the invention is substituted for a similar part, the actuating means of the machine operating the rivet setting arm of this invention without any change. Such actuating means do not enter into the invention and therefore will only be generally described as far as may be necessary to understand the application of the invention.

The machine comprises generally a C-shaped frame 10 provided with a head 12 in which is mounted a suitable motor operating a set 14 for vertical reciprocatory movement, the set exerting force downwardly against an anvil 16 mounted on the frame 10 below the set.

The anvil 16 has mounted usually therein a stem 18 which is projected upwardly against the work and locked to act as a punch when the set forces a die downwardly thereover but is freed to move downwardly into the anvil to form a part thereof under the pressure of the set when a rivet is to be upset in the hole previously punched. The stem 18 is of interest to the disclosure of this invention only in the latter capacity.

The head 12 carries a pair of cylinders fitted with plungers on one of which is mounted a die carrier. The other plunger carries a rivet setting arm 24 of this invention, this latter plunger cooperating in the actuation of the rivet setting arm.

The die carrying arm and the rivet setting arm are alternately swung into position below the set 14 when the latter is in raised position and first the die, and, on the next downward movement of the set 14, the rivet setting arm, are moved downwardly by the force exerted by the set acting against the action of springs tending to raise the plungers.

Referring to Figure 2, it will be noted that the rivet setting arm 24 of this invention comprises a unitary shoe 22 of considerable diameter for the purpose of mounting rivet positioning means, later described, and to act as a clamp upon the

work around the rivet during the final forming of the driven rivet head. It is pointed out that since shoe 22 is unitary and the work engaging face thereof smooth and unbroken and of considerable area, no marring of the sheet being riveted can occur.

Shoe 22 is provided with a central bore 26 having a diameter such that the heads of rivets of the size being used may slide easily through the shoe, the upper end of the bore preferably being flared to facilitate entry of rivets, stem first, into the bore. Set 14 is of such form as to fit easily in the bore and at the limit of its downward movement completely fills the bore, the lower end of the set being then level with the work face of shoe 22. The force to upset the rivet is applied by the work face of the set 14 to the rivet head and the force necessary to clamp the shoe 22 on the work is transmitted to the upper face of the shoe through shoulder 15 formed on set 14. The shoe 22 is provided with bores 28^a, 28^b, 28^c, of equal diameter extending radially from bore 26 to the outer surface of the shoe, the bores being arranged at equal angles to one another and in a common horizontal plane.

Pins 30^a, 30^b, 30^c, are mounted in bores 28^a, 28^b, 28^c with a sliding fit, the inward movement of the pins being limited by heads 32^a, 32^b, 32^c at the outer ends of the pins, and the pins being held against rotation in their movement by slots 34^a, 34^b, 34^c and threaded pins 36^a, 36^b, 36^c, fitted into tapped bores in the head and projecting into said slots.

The pins 30^a, 30^b, 30^c are normally held in inward position by a length of spiral spring 38 of small diameter which acts upon all three pins, being received in grooves 40^a, 40^b, 40^c in the heads of the pins. The upper portion of the inner end of each pin is formed with an inwardly and downwardly bevelled surface. The force exerted by the set when it engages the bevelled surfaces of the pins 30 or the head of a rivet 11 supported thereon is sufficient to overcome the resistance of a spring tending to raise the riveting arm, but is not sufficient to cause outward displacement of the pins until the shoe contacts the work.

The inner ends of the pins serve to support the rivet in the bore 26 until the set 14 in its downward movement holds the rivet between its lower face and the upper face of the punch member 18. The inner ends of pins 30^a, 30^b, 30^c are bevelled both to support the head of the rivet and also to act as cam surfaces for engagement by the set in its downward movement after shoe 22 rests upon the work to free the rivet for downward movement. The shoe shown in the drawings is used with a 100° countersunk rivet and the angle of the bevel on the pins is about 30°, but the angle of the bevel can, of course, be of any suitable degree. The rivet head, therefore, contacts the bevelled surfaces only at its uppermost circular edge, which avoids underscoring of the heads of the rivets. The length of the pins is such that when the pins are in inward position, the vertical faces at the inner ends of the pins form a triangular opening by which the rivets are maintained in vertical position to seat accurately upon the upper face of the punch 18 when the rivet is allowed to move downwardly in the shoe by the outward movement of pins 30^a, 30^b, 30^c caused by the inward movement of the set 14.

The depth of the shoe 22 and the level therein of the pins 30^a, 30^b, 30^c are such that the

rivet is supported in the shoe with its end projecting sufficiently below the lower face of the shoe to facilitate accurate positioning of the rivet in the rivet hole.

While the rivet setting arm of the invention has been described as used with 100° countersunk rivets it is obvious that the rivet setting arm can be adapted for use with other types of rivet. Accordingly a number of rivet setting arms are provided to enable one machine to handle different forms or sizes of rivet. It will be noted that the rivet setting arms and sets can readily be changed, as is common practice in riveting machines of this type.

In operation, the arm 24 swings to and from a rivet magazine during the rivet hole punching operation according to known practice, the rivet falling, stem first, into the central bore in the shoe 22 and coming to rest with its stem in the opening formed by the inner ends of pins 30^a, 30^b, 30^c and with its head supported on the bevelled surface formed on the upper portion of the inner ends of the pins. On the return from the rivet magazine, the shoe 22 is positioned above the punch means 18 in which the punch member has been freed from the positive abutment means which holds the punch during the punching operation. The punch means at this time is held in projecting position by the frictional grip of the punched metal and a spring, but can be forced downwardly to form the control portion of the bottom of a rivet head forming recess, by the downward movement of the rivet set during the rivet upsetting operation. The punch unit and the set are of conventional design, for which reason no more specific description of these parts is considered necessary.

When shoe 22 has been swung into rivet setting position and the rivet set has been brought into operation, the functioning of the rivet setting shoe of my invention is as follows:

In Figure 4 a flush head rivet commonly referred to as 100° countersunk rivet 11 is supported in shoe 22 by pins 30^a, 30^b, 30^c with the end of the rivet shank projecting slightly below the lower face of shoe 22 to facilitate accurate positioning of the rivet. The rivet set at this time is descending into the bore in the riveting shoe. As the rivet set continues downward movement the lower flat surface of the set strikes against the bevelled surface of the pins or against a rivet head resting on said bevelled surfaces, and as spring means tending to raise the rivet setting arm offer less resistance to displacement than the pins held inwardly by spring 38, the set moves the shoe 22 downwardly until the shoe rests upon the work. The continued downward movement of the set moves the pins radially outward, forcing the rivet ahead of it and driving the punch downward against the resistance of the aforementioned spring until the punch reaches the limit of its downward movement where it forms the central portion of the bottom of the recess in which the upsetting of the head now takes place. The rivet set continues downward movement until level with the lower surface of the shoe 12 which is resting upon the work, the forming of the driven head of the rivet being then completed. During the last phase of this operation shoulder 15 on the set engages shoe 22 to clamp it down upon the work, but due to the smooth unitary work face of shoe 22 no marring of the work can occur.

It will be noted that minor variations in the shape of the rivet head may cause the rivet set to engage the rivet head before it can strike

the beveled ends of the pins but the operation described is not in any way affected.

It is pointed out that a rivet of a given size is substantially held to a true position by a rivet setting arm designed for that size of rivet, since, even if the rivet head is released by the positioning pins and drops away from the rivet set for a brief interval before the rivet set again engages the head, this time interval is too short to permit material tilting of the rivet to occur.

It is also pointed out that the shoe 22 of the rivet setting arm is firmly pressed against the work during completion of the rivet upsetting operation, thereby guarding against deformation of the metal surrounding the rivet, but because of the smooth character of the extended area of the lower face of the unitary head and the flat surface of the rivet set which is level therewith, marring of the surface of the work is avoided.

The rivet setting arm of my invention as illustrated has proved very satisfactory in service but it is evident that various modifications of the illustrative embodiment herein described may be devised, as for instance, to enable rivets of varying sizes to be used without changing the setting arm and shoe. By using a suitable rivet setting arm and rivet set all types of rivets can be used and I claim all such modifications as may fall within the scope of the appended claims.

I claim:

1. A rivet setting device comprising: a unitary rivet setting shoe having a first uniplanar work face and a second, opposed face; a rivet receiving bore formed in said shoe and passing therethrough at right angles to said work face; means mounted on said shoe for disengageably supporting a rivet in said bore; and a rivet set having a shank portion of substantially the same diameter as said bore and reciprocable therein to force a rivet axially therethrough; said rivet set carrying an unyielding abutment for directly and positively engaging said second face to limit the inward movement of said set relative to said shoe and to positively force said shoe into pressure engagement with a work sheet; said abutment being spaced from the free end of said shank portion a distance equal to or less than the distance from the plane of said work face to the point of contact of said abutment with said second face; the area of said work face being larger than the cross sectional area of said bore.

2. A rivet setting device comprising: a rivet setting shoe having a first uniplanar work face for engaging a work sheet and a second, opposed face; a rivet receiving bore formed in said shoe and passing therethrough at right angles to said work face; means mounted on said shoe for disengageably supporting a rivet in said bore; and a rivet set having a shank portion of substantially the same diameter as said bore and recip-

rocable therein to force a rivet axially therethrough; said rivet set carrying an abutment at a fixed, predetermined position with respect thereto for directly engaging said second face to limit the movement of the set into the shoe and to positively force said shoe into pressural engagement with a work sheet; said abutment being spaced from the free end of said shank portion a distance equal to the distance from the plane of said work to the point of contact of said abutment with said second face; the area of said work face being larger than the cross sectional area of said bore; and said work face and the free end of said set combining to provide a uniplanar work face constituting in effect a solid bucking bar having a smooth contact face of considerably larger area than that of said set alone.

3. In combination with a riveting machine including mechanism to drive a reciprocatable rivet set: a rivet setting shoe having a uniplanar work face for engaging a work sheet; an abutment on said shoe spaced from said work face; a rivet receiving bore formed in said shoe and passing therethrough at right angles to the work face; means on said shoe for disengageably supporting a rivet in said bore; and a rivet set having a shank portion of substantially the same diameter as said bore and drivable by said mechanism to reciprocate in said bore and drive a rivet axially therethrough; the free end of said shank portion having a flat face at right angles to the shank axis; an abutment on said set at a predetermined distance from the free end adapted to engage the abutment on said shoe to limit the telescoping action of said set and shoe and to force said shoe into pressural engagement with a work sheet; said predetermined distance being equal to the distance from the work face of said shoe to the abutment on said shoe; said work face and the free end of said set combining to provide a uniplanar work face constituting in effect a solid bucking bar having a smooth contact face considerably larger than that of said set alone drivable by said mechanism into contact with a work sheet and a rivet therein.
